(57) **CLAIM**

The ornamental design for a mounting clip, as shown and described.

DESCRIPTION

FIG. 1 is a perspective front view of a mounting clip;

FIG. 2 is a perspective back view thereof;

FIG. 3 is a top view thereof;

FIG. 4 is an elevated back view thereof;

FIG. 5 is an elevated side view thereof;

FIG. 6 is an elevated front view thereof;

FIG. 7 is a bottom view thereof;

FIG. 8 of another embodiment is a perspective front view thereof;

FIG. 9 is a perspective front view thereof;

FIG. 10 is a top view thereof;

FIG. 11 is an elevated front view thereof;

FIG. 12 is an elevated side view thereof;

FIG. 13 is an elevated back view thereof; and,

FIG. 14 is a bottom view thereof.

A left side elevational view is provided of which the right side elevational view is identical.
